UNITED STATES PATENT OFFICE.

FREDERICK WEHINGER, OF WATERBURY, CONNECTICUT, ASSIGNOR TO WATERBURY CLOCK CO., OF WATERBURY, CONNECTICUT, A CORPORATION.

CHIME-CLOCK.

1,304,924.

Specification of Letters Patent. Patented May 27, 1919.

Application filed February 21, 1918. Serial No. 218,409.

To all whom it may concern:

Be it known that I, FREDERICK WEHINGER, a citizen of the United States, residing at Waterbury, in the county of New Haven 5 and State of Connecticut, have invented a new and useful Improvement in Chime-Clocks; and I do hereby declare the following, when taken in connection with the accompanying drawings and the characters 10 of reference marked thereon, to be a full, clear, and exact description of the same, and which said drawings constitute part of this application, and represent, in—

Figure 1 a view in left hand edge elevation 15 of a chime-clock constructed in accordance with my invention.

Fig. 2 a view thereof in front elevation.

Fig. 3 a view thereof in vertical section 20 on the line 3—3 of Fig. 1 looking from front to rear.

Fig. 4 a similar view showing the chime-train after it has been warned and prior to its release, and the chime cut-out lever in its operative position in which it cuts out 25 the chiming hammers.

Fig. 5 a detached perspective view in rear elevation of the four-point warning and releasing chime-cam, showing its turn-back bevels.

Fig. 6 a detached perspective view of the 30 lifting lever which co-acts with the said cam.

Fig. 7 a perspective view of the chime cut-out lever.

35 My invention relates to an improved chime-clock, the object being to reduce the width of the movement so as to permit it to be introduced into a relatively small case, to make its parts accessible for adjustment 40 and repair, and to reduce the cost of its production.

With these ends in view, my invention 45 consists in a chime-clock characterized by having front, rear and intermediate movement-plates spaced apart to form front and rear train-spaces, and by having a time-train and a strike-train located in such front train-space, and a chime-train in such rear train-space.

50 My invention further consists in a chime-clock in which the time, chime and strike-trains are so interrelated that the chime-train will be warned and released by the time-train, and so that the strike-train will

be warned by the time-train after the chime-train has been warned, and released by the chime-train after the chime has been rung.

My invention further consists in certain details of construction and combinations of parts as will be hereinafter described and 60 pointed out in the claims.

In carrying out my invention as herein shown, I employ a front movement-plate 4, intermediate movement-plate 5, and a rear movement-plate 6, the said plates being 65 spaced apart by pillars 7 to produce a front train-space 8 and a rear train-space 9. In the front train-space 8, I locate the time- and strike-trains which may be of any approved construction, and in the rear train-space 9, the chime-train, also of any approved construction, and provided with a chime-drum 10 mounted on an arbor 11 journaled in the said plates 5 and 6 and set with chime-pins 12 co-acting with hammer- 75 operating fingers 13 extending inwardly from hammer-hubs 14 provided with hammer-wires 15 carrying hammers 16. The said hubs 14 are mounted upon an arbor 17 supported at its ends in the plates 5 and 6, 80 and also mounting at its forward end a hub 18 provided with a hammer-wire 19 carrying a strike-hammer 20 which is operated independently of the chime-drum 10 as will be hereinafter described.

85 It will be seen from the foregoing that I locate in the rear train-space 9 of my improved clock, not only the chime-train, but also the entire battery of chime-hammers 16 as well as the chime-hammer 20 and the 90 various parts required for the mounting and operation thereof, whereby I am enabled to reduce the width of the movement without substantially increasing it in thickness from front to rear over an ordinary chime-clock 95 in which the time, strike and chime-trains are arranged side by side in line between the front and back movement-plates and in which the hammer battery and the parts for mounting and operating the same are 100 located entirely back of the back movement-plate in an exposed and unprotected position where they virtually increase the thickness of the movement. I am thus enabled to reduce the width of the movement without substantially increasing it in thickness over clocks of the prior art in which an exposed hammer-battery located back of the 105

back movement-plate virtually doubles the depth of the movement so far as the problem of casing is concerned.

The center arbor 21 which is journaled in the plates 4 and 5, mounts a warning and releasing chime-cam 22 having four equidistant points 23 the rear faces of which are formed with turn-back bevels 24 co-acting with a beveled finger 25 upon the offset end 26 of a sheet-metal lifting-lever 27 mounted upon a chime-warning arbor 28 journaled between the plates 5 and 6 and forming a part of the lock-work of the chime-train. (I may here say that I use the term "lock-work" in the sense in which it is generally used by clock-makers to designate the arbors, wires and co-acting parts employed to control the stopping and releasing of the strike-and chime-trains of clocks.)

The arbor 28 mounts a lifting-hook 29 extending under a chime count-hook 30 mounted in a chime-locking arbor 31 journaled in the plates 5 and 6 at a point substantially above the arbor 28. The said hook 30 co-acts with a chime count-wheel 32 mounted upon the third wheel arbor 33 of the chime-train, the said arbor being journaled in the plates 5 and 6 and carrying the third wheel 34 which meshes into a wheel 35 on the arbor 11 and so drives the chime-drum 10. At its rear end the arbor 33 mounts a pinion 36 meshed into by the second wheel 37 of the chime-train, the said wheel being mounted upon the second arbor 38 of the said train, and the said arbor having a pinion 39 meshed into by the main wheel 40 mounted upon the chime-winding arbor 41, also mounting the chime-spring 42. The third wheel 34 of the chime-train meshes into a pinion 43 on the arbor 44 of the fourth wheel 45 which meshes into a pinion 46 on the arbor 47 of the fifth wheel 48 which meshes into a pinion 49 on the arbor 50 mounting a fly 51, all of the parts last mentioned belonging to the chime-train. The fourth wheel 45 carries a locking-pin 52 co-acting with the hooked end of a locking-wire 53 mounted in the chime-locking arbor 31 and raising a lifting-hook 54 mounted in a strike-warning arbor 55 journaled between the plates 5 and 6 and mounting at its forward end a strike-warning wire 56 which reaches forward through the intermediate movement-plate 5 and co-acts with a locking-pin 57 in the fourth wheel 48 of the strike-train which is located in the front train-space 8. The fifth wheel 48 of the chime-train carries a chime-warning pin 59 co-acting with the bent end of a chime-warning wire 60 which is mounted in the chime-warning arbor 28.

The center arbor 21 also mounts a one-point strike cam 61 located in the front train-space 8 at a point in front of the

chime-cam 22 and operating once an hour upon the bent lower end of a strike lifting-wire 62 depending from an arbor 63 journaled between the plates 4 and 5 and provided at its forward end with a hook 64 which operates to lift a strike count-hook 65 mounted in the forward end of a count-hook arbor 66 journaled between the plates 4 and 5, the flattened outer end of 67 of the count-hook co-acting with an ordinary strike count-wheel 68 concentric with the strike-winding arbor 69.

The count-hook arbor 66 mounts the strike locking-hook 70 the bent outer end of which co-acts with the strike locking-pin 57 aforesaid. The said arbor 66 also mounts a cam-hook 71 which co-acts with a cam 72 mounted upon the arbor 73 of the third wheel 74 of the strike-train, the function of the hook 71 and cam 72 being to lift the flattened end 67 of the strike count-hook 65 clear of the teeth of the strike count-wheel 68 in the usual manner. A tripping wire 75 depending from the hook 64 provides for manually starting the strike-train so as to synchronize it with the time-train when required.

The strike third wheel arbor 73 projects at its rear end through the intermediate plate 5 and is provided with a hub 76 carrying two strike-pins 77 which engage with the hooked outer end of the strike hammer-tail 78 mounted in the strike-hammer hub 18 aforesaid, whereby the strike-hammer 20 is operated when the strike-train is released, for striking the hour.

The strike-train is driven by a strike main spring 79 located in the space 8, mounted upon the strike winding-arbor 69 and driving the main wheel 80 of the strike-train, the said wheel 80 meshing into a lantern pinion 81 on the arbor 82 of the second wheel 83 of the strike-train. The said arbor 82 is furnished at its forward end with a pinion 84 which meshes into, and drives the count-wheel 68. The said second wheel 83 meshes into a pinion 85 on the third wheel arbor 73 carrying the third wheel 74 which meshes into a pinion 86 upon the arbor 87 of the fourth wheel 58 of the strike-train, the said wheel 58 meshing into a lantern pinion 88 upon the arbor 89 carrying the fly 90. The parts last described form the strike-train and are located within the front train-space 8.

The time-train, also located within the front train-space 8, consists, as herein shown, of a main wheel 91 driven by a time spring 92 on the time winding-arbor 93 journaled in the plates 4 and 5. The wheel 91 meshes into a pinion 94 on the arbor 95 of the second wheel 96 which meshes into a pinion 97 on the arbor 98 of the third wheel 99 which meshes into a pinion 100 on the arbor 101 of the fourth wheel 102 which

meshes into a pinion 103 on the arbor 104 of an escapement-wheel 105 co-acting with a verge 106 on the verge arbor 107. The second wheel 96 of the time-train meshes into 5 a center wheel 108 on the center arbor 21 and drives the same. The arbor 21 is provided with a cannon pinion 109 meshing into a minute-wheel 110 mounted on an arbor 111 carrying a pinion 112 which meshes 10 into an hour-wheel 113 carrying an hour-socket 114, this dial-work, so called, being located directly back of the front movement-plate 4.

To enable the user of the clock to cut out, 15 and so silence the chime at any time, I employ an arbor 115 mounted in the plates 5 and 6 and designed to project through the dial (not shown) for the application of a key to its squared forward end. This arbor is provided at its rear end with a hub 116 located within the rear train-space 9 and furnished with an operating and locking pin 117 co-acting with an inclined operating face 118 upon the upper end of a locking 20 cut out lever 119 also furnished at its upper end with an overhanging hook 120 having a locking stop-notch 121. The said lever is hung upon a stud 122 and formed at its lower end with a rearwardly turned 25 arm 123, the upper edge of which normally stands adjacent to the inner ends of the hammer-wires 15 of the chime-hammers 16, the arm being cut away as at 124 to clear the strike hammer-wire 19 so as to prevent the 30 same from being effected by the operation of the lever 119.

It will be seen from the foregoing description that although the strike and chime-trains are located on opposite sides of the 40 intermediate movement-plate 5, their lock-work is interrelated so that the chime-train may be utilized for controlling the release of the strike-train, although the same is warned in the usual manner by the time-train 45 whereby the operation of the strike-train is brought into proper sequence with the operation of the chime-train, and also whereby the chime-train is relieved of the burden of warning the strike-train which my 50 invention devolves upon the time-train.

For the purpose of describing the operation of my improved chime-clock, it may be assumed that one of the points 23 of the four-point chime-cam 22 has lifted the lifting lever 27, whereby the chime-warning arbor 28 is rocked and the chime-warning wire 60 lifted into the path of the chime-warning pin 59 in the fifth wheel 48 of the chime-train. At the same time, the lifting-hook 29 55 acts to lift the chime count-hook 30 out of one of the notches in the chime count-wheel 32. Through the lifting of the count-hook 30, the chime-locking arbor 31 is rocked to lift the hook 53 out of the path of the locking-pin 52 in the fourth wheel 45 of the 60 chime-train. When the locking-pin 52 is released, the chime-train is driven by its spring 42 until the warning-pin 59 is engaged with the upturned end of the chime-warning wire 60, as shown in Fig. 4. The 70 chime-train is now warned. The action just described, takes place immediately previous to every quarter hour, and every time it takes place the rocking of the arbor 31 acts through the chime-locking wire 53 to raise 75 the lifting-hook 54 and so rock the strike warning-arbor 55 carrying the strike warning-wire 56 which is lifted into the path of the strike locking-pin 57 in the fourth wheel 58 of the strike-train. However, such periodic lifting of the hook 54 is without effect except on the hour or in other words, at the conclusion of the fourth quarter, when directly after the warning of the chime-train as described, the single point strike-cam 61 80 will operate through the strike lifting-wire 62 to unlock the strike-train which will now start and run until its pin 57 has been brought into engagement with the bent end of the strike warning-wire 56 which has 85 been brought into its path by the rocking of the strike-warning-arbor 55 by the action of the chime lock-work as previously described. The strike-train having thus been warned by the action of the time-train, is 90 now held in readiness to be released by the action of the chime-train after the conclusion of the chiming operation.

The chime-train having thus been warned as described, at the conclusion of the quarter, 100 whatever quarter it may be, the lifting-lever 27 will drop off the particular point 23 now in play of the chime-cam 22. The lever 27 will now fall and permit the chime warning-wire 60 to drop downward out of the path of the warning-pin 59 and thus permit the chime-train to run through its chiming phase and ring the chimes. During this time, the chime locking-wire 53 will be held in its elevated position in which it clears the locking-pin 52, by the riding of the chime count-hook 30 upon the periphery of the chime count-wheel 32, whereby the locking-hook 53 is prevented from co-acting with the locking-pin 52 until the count-hook 30 has been given 110 the opportunity of dropping into the succeeding notch of the count-wheel 32 which takes place at the conclusion of the chiming phase. When the count-hook 30 drops into the notch as described, it permits the strike 115 warning-arbor 55 to rock, and hence the strike warning-wire 56 to drop down out of the path of the strike locking-pin 57 in the fourth wheel 58 of the strike-train. Now if the strike-train has been previously warned 120 by the time-train, which will be the case if the chimes were last rung on the hour, it will be released by the chime-train for striking the hour, which will be done in the usual manner under the control of the count wheel 125 130

of the strike-train. It will thus be seen that under my invention, the strike-train after having been warned by the time-train after the warning of the chime-train by the time-train, is released by the action of the chime-train when the same has completed the ringing of the chimes. The mechanism employed to release the strike-train by the chime-train operates every quarter, but is only effective when the operation of the time-train has previously effected the warning of the strike-train, which is done only on the hour.

In setting the clock, it is often desirable to turn the hands counter clockwise. This is provided for without deranging the mechanism, by forming the points 23 of the cam 22 with turn-back bevels 24 which act upon the hook 25 of the lever 27 to spring the same laterally, permitting the points 23 to ride past it, without deranging the mechanism.

To silence the chimes, it is only necessary to apply a key to the projecting squared forward end of the cut-out shaft 115 and turn the same counter-clockwise, whereby the operating and locking pin 117 acting upon the face 118 of the cut-out lever 119 rocks the same on its stud 122 and causes its bent lower end to rock the hammer-hubs 14 so as to clear their fingers 13 from the action of the chime-pins 12, as shown in Fig. 4, the lever 117 being locked in this position by the entrance of the pin 117 into the bottom of the notch 121 formed by the overhanging hook 120. On the other hand, by applying the key to the shaft 115 and turning the same clockwise, the lever is allowed to drop into its re-tired position in which the chimes are permitted to sound and in which the lever is locked by the entrance of the pin 117 into the locking notch 125 in the edge of the hook 120 of the lever as shown in Fig. 3.

As shown, the hammers are arranged to ring chimes located in the bottom of the clock-case. They may, however, be constructed and arranged to ring chimes located upon either side of the case or within the top thereof, these being details not connected with my present invention.

I claim:—

50 1. A chime clock characterized by having three movement-plates spaced apart to form front and rear train-spaces and by the location of the time and strike trains side by side in the said front train-space and the location 55 of the chime-train and hammer-battery within the said rear train-space.

2. A chime-clock characterized by having a time-train, a chime-train, and a strike-train forming a unitary organization, in which 60 the chime-train is warned and released by the time-train, and in which the strike-train is warned by the time-train and released by the chime-train.

3. In a chime-clock, the combination with 65 time, chime and strike-trains all constructed

and interrelated for sequential co-action so that after the chime-train has been warned by the time-train, the strike-train will be warned by the time-train on the hour and so that after the chime-train has operated to ring the chime it will release the strike-train.

4. A chime-clock characterized by having the lock-work of its chime-and strike-trains so interrelated for sequential co-action that the lock-work of the chime-train acts upon the lock-work of the strike-train to release the same after the same has been warned by the time-train and after the chime-train has operated to ring the chimes.

5. In a chime clock, the combination with 80 three movement-plates spaced apart to produce a front train-space and a rear train-space, of time and strike trains located side by side in the said front train-space, and a chime-train and battery of chime-hammers 85 located in the said rear train-space, the lock-work of the said chime and strike trains reaching through the intermediate movement-plate for their interrelation and co-action.

6. A chime-clock having three movement-plates spaced apart to produce front and rear train-spaces, a time-train and a strike-train located in the front train-space, and a chime-train in the rear train-space, the 95 center-arbor of the time-train being journaled in the front and intermediate movement-plates and mounting a one-point strike-cam and a four-point chime-cam.

7. In a chime clock, the combination with 100 front, rear and intermediate movement-plates spaced apart to form front and rear train-spaces, of time and strike trains located side by side in the said front train-space, a chime-train located in the rear 105 train-space, and a battery of hammers including the chime-hammers and the strike-hammer also located within the said rear train-space and rocking on a stud mounted at its ends in the said intermediate and rear movement-plates.

8. A chime clock having time, chime and strike-trains, a cut-out arbor projecting forward through the front movement-plate of the clock for manual operation, and a cut-out lever operatively related to the inner end of the said arbor and to the hammers of the chime-train.

9. In a chime clock, the combination with 115 the chime-train and the hammers thereof, of a manually operable cut-out arbor, a cut-out lever interposed between the said arbor and the said hammers for preventing the same from operating, and locking means for locking the said cut-out lever in the position in which it leaves the said hammers free to operate.

10. In a chime clock, the combination with 120 the chime-train and the hammers thereof, of a manually operable cut-out arbor, a cut- 125

out lever interposed between the inner end of the said arbor and the said hammers, and locking means mounted upon the said arbor and engaging with the upper end of the 5 said lever for locking the same in the position in which it leaves the said hammers free to operate.

11. In a chime clock, the combination with the chime-train and the hammers thereof, of 10 a manually operable cut-out arbor, a hub at the inner end thereof, and a cut-out lever interposed between the said hub and the said hammers and formed at its upper end with an operating face, a stop-notch and a 15 locking-notch.

12. In a chime clock, the combination with the chime-train and the hammers thereof, of 20 a manually operable cut-out arbor, a hub at the inner end thereof, a cut-out lever interposed between the said hub and the said 25 hammers and formed at its upper end with

an inclined operating face, a stop-notch, and a hook containing a locking-notch; and a pin mounted in the said hub and co-acting with the said inclined face, stop-notch and locking-notch, whereby the lever is moved into position to prevent the said hammers from operating by the action of the said pin upon the said face, and locked in such position by the entrance of the said pin into the 30 said locking-notch, and whereby the reverse turning of the hub is arrested by the entrance of the said pin into the said stop-notch.

In testimony whereof, I have signed this 35 specification in the presence of two subscribing witnesses.

FREDERICK WEHINGER.
